UNITED STATES PATENT OFFICE.

WILLIAM B. HENRI, OF CHICAGO, ILLINOIS.

MAILING-FOLDER.

1,060,596.

Specification of Letters Patent.

Patented May 6, 1913.

Application filed April 29, 1912. Serial No. 693,971.

To all whom it may concern:

Be it known that I, WILLIAM B. HENRI, a citizen of the United States, residing at the city of Chicago, in the county of Cook 5 and State of Illinois, have invented a new and useful Improvement in Mailing-Folders, of which the following is a specification.

My invention relates to folders made of cardboard which are distributed by mail for advertising purposes, and which are provided with a detachable portion used as a mailing card to be returned to the sender. It is necessary that the relatively movable parts or flaps of such device shall be secured 15 together to make a rigid package, and so as to prevent the overlapping portions from being broken or torn. If the latter takes place certain portions, including address or stamp may become detached and the folder 20 thereby fail of delivery. The securement of these parts together has usually been done by the use of ties, bands or metallic clips. The latter, however, are particularly objectionable, as they have been known to destroy 25 the dies of stamp canceling machines, and the use thereof is not satisfactory to the postoffice authorities.

My invention provides means by which the integral portions of the card itself are used to secure the outer flap. It is so designed as to insure the address always being printed or written in the proper place with the minimum of time and maximum of speed either by hand or machine. It includes 35 a detachable return mailing card, which is a part of the folder, and so related to the other parts thereof that the recipient is saved the trouble of signing or addressing the return postcard, the original mailing address becoming a pre-signature when detached. As the card is also provided with a return address, it only remains for the person receiving the same to write the message and post the detached card.

40 The principles of my invention are illustrated in the drawings, in which—

Figure 1 is a perspective view of my improved mailing card when partially open;

Fig. 2 shows the same when closed; Fig. 3 45 is a reverse view of Fig. 1, the same being turned end for end; Fig. 4 shows the card illustrated in Fig. 1 as laid flat before folding; Fig. 5 represents a somewhat modified form of the card as shown in Fig. 1.

50 Further describing my invention with reference to the drawings, in which like char-

acters of reference denote like parts throughout: 1 is the body portion; 2 the inner flap, and 3 the outer flap of my improved mailing card. One end of the same, including the 50 right hand lower portion, upon which the address should properly be placed, should be partially separated from the remainder of said flap by a line 4 of perforations or scored by a cutting rule, as well as on the 55 line indicated by 5. The said part 6 should carry on the inside the address of the sender, while the other side may be in any form desired, but having a blank space at the portion adjacent to line 5 upon which the original 60 mailing address is entered as shown at 7 in Fig. 3. A tongue 8 may be formed by cutting through the flap 2 on the lines 9, 10, and 11, thereby allowing the said tongue 8 to spring outwardly on the uncut line 12. 70 This tongue obviates the necessity of using 75 clips, thus cutting down the cost of the finished product. It forms a stop whereby the flap 3 is not permitted to go beyond the normal portion appropriated to the pre-signature address, and where the edge of the tongue coincides with the dotted line 4 the postcard section is much easier to detach as the edge is cut clear through instead of being merely scored or perforated.

80 When the device is provided with the desired printed matter, the mailing address is inserted in the proper position as above described, the lower flap is folded upon the line 5'; the upper flap is folded down thereon on 85 the line 3', and the edge 3'' is inserted under the tongue 8 with the same motion. This renders the folder ready for addressing and mailing with two folding operations where three or more are required when the folder 90 is clipped or otherwise secured. The oblong space bounded by the lines a, b, c and d as shown in Fig. 2, should be almost identical in size with the ordinary addressing machine stencil with which such folders are 95 largely addressed. Such quadrilateral being clearly defined insures the address being put exactly in the right place on the lower portion of the card. If this space is not so outlined the operation of the addressing machine very often allows the address to be printed partially on the postcard and partially over the edge, whereby the address signature is mutilated or destroyed when detached.

100 In the modified construction set forth in Fig. 5, the elements 1', 2', 3', 3'', 3''', 5', 5'',

4', and 6' are of a form identical to that set forth in the preferred construction by the following numerals respectively 1, 2, 3, 3', 3'', 4, 5, 5', and 6. Said modified construction only differs in that the member 8 thereof is at a point within the flap 2' somewhat removed from the scoring 4' whereas in the preferred construction, it borders upon the scoring 4. The operation of both 10 constructions herein described are identical.

I claim:

1. A mailing folder comprising a body portion, an inner flap and an outer flap, said inner flap having one end scored its entire 15 width to provide a detachable postcard and also provided with an integrally formed rectangular longitudinally extending member cut free at one edge on the line of said scoring and also cut free at two of its other 20 edges and adapted to resiliently engage the lower edge of said outer flap.
2. A mailing folder comprising a body

portion, an inner flap, an outer flap, said inner flap having a scoring at one end forming a portion adapted to be detached and provided with a return address on the inside thereof, a space upon the other side of said portion adapted for receiving a sending address constituting a pre-signature, said outer flap being shorter than and adapted to overlap the inner flap and said inner flap being provided with an integrally formed member cut free at three of its edges, one of said cut edges corresponding with said scoring and said member being adapted to resiliently engage the lower edge of said outer flap.

In witness whereof, I have hereunto subscribed my name, this 25th day of April A. D. 1912, in the presence of two subscribing witnesses.

WILLIAM B. HENRI.
